CLAIM

The ornamental design for a tire valve, as shown and described.

DESCRIPTION

FIG. 1 is a perspective view of a tire valve showing my new design;

FIG. 2 is a left side view of the tire valve shown in FIG. 1; FIG. 3 is a right side view of the tire valve shown in FIG. 1;

FIG. 4 is a front view of the tire valve shown in FIG. 1; FIG. 5 is a back view of the tire valve shown in FIG. 1; and, FIG. 6 is a top view of the tire valve shown in FIG. 1.

1 Claim, 5 Drawing Sheets## Related U.S. Application Data

17/160,320, filed on Jan. 27, 2021, now Pat. No. 11,719,351, said application No. 18/106,743 is a continuation of application No. 17/160,320, filed on Jan. 27, 2021, now Pat. No. 11,719,351, said application No. 18/132,038 is a continuation-in-part of application No. 17/160,320, filed on Jan. 27, 2021, now Pat. No. 11,719,351, said application No. 18/105,303 is a continuation of application No. 17/160,320, filed on Jan. 27, 2021, now Pat. No. 11,719,351, said application No. 18/121,947 is a continuation-in-part of application No. 17/160,320, filed on Jan. 27, 2021, now Pat. No. 11,719,351, said application No. 18/106,745 is a division of application No. 17/160,320, filed on Jan. 27, 2021, now Pat. No. 11,719,351.
